FIG. 1 is a front elevational view of a frame with an insert disposed in the frame in accordance with an embodiment of my design;

FIG. 2 is a rear elevational view thereof;

FIG. 3 is a front perspective view thereof;

FIG. 4 is a rear perspective view thereof;

FIG. 5 is a top plan view thereof;

FIG. 6 is a bottom plan view thereof; and,

FIG. 7 is a right side elevational view thereof, wherein the left side elevational view is identical.

The broken lines in the figures are for the purpose of showing environmental structure and form no part of the claimed design.
